(57) **CLAIM**

The ornamental design for a box of storage shelf as shown and described.

DESCRIPTION

FIG. 1 is a top front perspective view of a box of storage shelf showing my new design;

FIG. 2 is a front view thereof and the rear view being a mirror image;

FIG. 3 is a left side view thereof and the right side view being a mirror image;

FIG. 4 is a top view thereof;

FIG. 5 is a bottom view thereof; and,

FIG. 6 is a bottom front perspective view thereof.

The dashed broken lines in the figures show portions of the box of storage shelf that form no part of the claimed design.

1 Claim, 4 Drawing Sheets
